(57) **CLAIM**

The ornamental design for a display screen or portion thereof with animated graphical user interface as shown and described.

DESCRIPTION

1. Display screen or portion thereof with animated graphical user interface

1.1 : First image in a sequence

1.2 : Second image in a sequence

Broken lines in the figures illustrate portions of the graphical user interface that form no part of the claimed design; the appearance of the animated graphical user interface sequentially transitions between the images shown in figures 1.1 through 1.2.

(Continued)

The process or period in which an image transitions to another forms no part of the claimed design.
